ELEVATING-TRUCK.

1,338,255.

Specification of Letters Patent. Patented Apr. 27, 1920.

Application filed June 14, 1916. Serial No. 103,603.

To all whom it may concern:

Be it known that I, BERNARD E. SCRIVEN, a citizen of the United States, residing at 2 North Eighth avenue, Mount Vernon, in 5 the county of Westchester and State of New York, have invented certain new and useful Improvements in Elevating - Trucks; and I do hereby declare the following to be 10 a full, clear, and exact description of the invention, such as will enable others skilled in the art to which it appertains to make and use the same.

The present invention relates to that class 15 of trucks in which the load is supported on a vertically movable table which may be raised to transfer the load to the truck, or which may be lowered to transfer the load from the truck to another support.

The object of the invention is to provide 20 novel and improved mechanism for raising and lowering the table of this type of truck which will enable the load to be readily and conveniently handled with comparatively little exertion on the part of the operator.

25 A further object of the invention is to provide novel and improved means for connecting the table raising and lowering mechanism with a guiding handle, so that the latter may serve not only for guiding the 30 truck, but also for actuating the table raising and lowering mechanism. A still further object of the present invention is to improve and simplify the table raising and lowering mechanism shown and described 35 in the patent to Adam, No. 1,210,252, granted December 26, 1916.

To these ends the invention consists in the features of construction and combination of parts hereinafter described and referred to in the claims.

In the accompanying drawings which illustrate what is now considered the preferred form of the present invention, Figure 1 is a plan view of my improved truck; 45 Fig. 2 is a vertical longitudinal section on line 2—2 of Fig. 1; Fig. 3 is a transverse vertical section on line 3—3 of Fig. 1; Fig. 4 is a transverse vertical section on line 4—4 of Fig. 1; Fig. 5 is a longitudinal section of the retarding device for checking the downward movement of the table, and Fig. 6 is an enlarged sectional view of one 50 of the details of construction.

The carriage or running gear of my improved truck comprises an A-shaped frame

formed by the obliquely-arranged side members 1 and the cross member 2. The side members are supported at their rear ends upon the rear axle 3, and at their front ends upon the rigid front axle 4. The truck 60 is supported upon four wheels, the rear wheels 5 being mounted upon the ends of the rear axle 3, while the front wheels 6 are mounted upon short spindles 7 carried by the steering knuckles 8 pivotally supported in the yokes 9 secured to each end of the fixed front axle 4. The steering knuckles 8 turn upon a hollow vertical bearing or pivot 10 secured in the yoke 9, the pivot having its bore enlarged at its lower 70 end for a purpose shortly to be described. The steering knuckles are turned by means of a guiding handle 11 mounted in the slot or recess in the block 13 secured to the front axle 4 at its middle, and arranged to 75 turn about a vertical pivot pin 12. A cross member 14 fixed upon the handle is connected by means of the links 15 to the arms 16 extending from the steering knuckles 8. As the guiding handle is turned to the right 80 or to the left, the front or steering wheels 6 are turned in a corresponding direction about the hollow steering pivots 10.

The vertically movable table of the truck 85 comprises an open frame 18 of angle iron with integral side and end members, and with cross members 19 and 20 secured to the side members and located directly over the front and rear axles respectively. The table is guided at its front end so that it 90 will move directly up or down by means of the guide rods 21 secured in the cross member 19, and vertically movable in the hollow steering pivots 10. The head 22 of the guide rod moves in the enlarged lower end 95 of the bore and limits the extent of upward movement of the table. The table is guided at its rear end by means of a hollow downwardly projecting boss 24 secured to the cross member 20, the boss sliding upon an 100 upwardly extending cylindrical member 25 fixed upon the rear axle 3 at its middle. The member 25 is counterbored to receive the headed bolt 26, the end of which is secured to the washer resting upon the cross 105 member 20, and the shank passing through a head 27 which closes the end of the bore in the member 25, thus forming a stop for limiting the upward movement of the rear end of the table.

The mechanism for raising and lowering the table comprises four wedges having inclined upper and lower edges, and adapted to be moved longitudinally between rolls 5 carried by the axles and the table. The two front wedges 29 are formed integrally with cross members 30 and 31, and are arranged to move with their lower edges supported upon the rolls 32 free to turn upon 10 the front axle between the side members 1 of the frame and the block 13 which carries the steering handle, and with their upper edges in engagement with the rolls 33 pivotally supported between the brackets 34 15 secured to the cross member 19 and extending downwardly beyond the periphery of the rolls a sufficient distance to guide the wedges and prevent lateral movement. The members 1 and block 13, it will be noted, 20 extend above the periphery of the rolls 32, and also serve as guides to prevent lateral movement of the wedges.

The rear wedges 36 are connected together at their front and rear ends by the cross 25 rods 37 and 38, and are also connected at their front ends with the front wedges 29 by means of the rods 39 connected at their middle by the cross brace 40, the whole forming a rigid frame. The lower edges of 30 the rear wedges 36 are supported upon the rolls 41 rotatably mounted upon the rear axle 3 between the side members 1 and the sleeves 42. The upper edges of the wedges 36 engage the rolls 43 supported by the 35 brackets 44 secured to the cross piece 20. The rear wedges are guided and held from lateral movement in a manner similar to the front wedges by means of the downwardly projecting lower edges of the brackets 44 and the upwardly extending members 1.

In my prior application above referred to, the wedge frame is actuated to elevate and lower the table by means of a handle 45 or lever separate from and independent of the guiding handle. In the present invention such separate actuating lever or handle has been dispensed with, the wedge frame being actuated by the guiding handle itself 50 through the following mechanism: Pivoted upon the pin or rod 45, which is mounted in the front ends of the front wedges 29, is a link or member 46 (see Fig. 6) consisting of the side bars 47 connected by the 55 hollow rod or bearing sleeve 48 and the several pins or rods 49, 50, and 51. The rear ends of the side bars 47 are notched as indicated in dotted lines in Fig. 2 to provide an overhanging shoulder 52 arranged to engage 60 a stop rod 53 extending across from one of the side wedges 29 to the other to limit the upward movement of the front end of the link or member 46, the downward movement being limited by a stop piece 54 mounted 65 upon rods 45 and 53, the front end of

which is projected forwardly and downwardly beneath the rod 51. The link is normally held in substantially horizontal position with the shoulder 52 in engagement with the rod 53 by means of a leaf spring 70 55, one end of which is secured around the rod 51, while the free end passes beneath the rod 56, the spring bearing near its anchored end upon the top of the stop piece 54.

Pivoted at the forward end of this link 75 is a second link or lever 57 comprising the side bars 58 connected by the rod or pin 59 which passes through and turns within the sleeve or tube 48. The side bars 58 are also connected by the rods 60 and 61, the latter 80 of which serves to anchor one end of the coiled spring 62 which surrounds the tube 48, the other end of the spring being held beneath the pin or rod 49, the ends of which project from the side members 47 of link 46 85 to form stops to limit the movement of the second link 57. The link or lever 57 thus normally tends to swing to a substantially vertical position, as shown in Fig. 2. The side bars 58 are each provided with a hook-shaped recess 63 adapted to receive the pins 64 upon the guiding handle 11 when the latter is swung upwardly about the horizontal pivot 65. The projections 66 extending outwardly from the free end of the side bars 58 of the 90 lever 57 afford a convenient means for swinging the lever down either by the hand or by the foot of the operator to connect the lever and the handle, which connection, it will be observed, when once made will be maintained 95 while the handle is being depressed, but which will be automatically broken when the handle is raised. From the foregoing description it will be evident that when it is desired to elevate the table it is only necessary to raise the handle, hook the lever 57 over the pins 64, and then depress the handle, thus drawing the wedge frame forward and raising the table. The forward movement of the wedge frame is sufficient to 100 bring the notches in the upper and lower edges of the front wedges into engagement with the rolls, thereby preventing rearward movement of the wedge frame under the weight of the table and load when the handle is released. If the handle 11 be now 105 raised, the lever or member 57 through the action of the spring 62 will be automatically disconnected, leaving the handle free to be swung to one side or to the other, and to be 110 raised and lowered to a sufficient extent for the proper guidance and manipulation of the truck.

The wedge frame is also actuated in the opposite or rearward direction to lower the 115 table by means of the guiding handle which when swung upwardly and rearwardly will bring the handle into direct engagement with the forward end of the link 46, and force the link and wedge frame rearwardly 120 130

a sufficient distance to carry the grooves in the upper and lower edges of the front wedges out of engagement with the rolls, after which the weight of the table and load 5 will cause the further and complete rearward movement of the wedge frame.

In order to prevent this movement from being too rapid, with the possibility of damage to the truck by the sudden stopping of 10 the wedge frame or of the descending table, a retarding device has been provided which comprises a cylinder 67 pivoted at its rear end to the cross bar 2 on the frame. Within 15 the cylinder is the piston 68 (see Fig. 5) and connecting rod 69, the end of which projects through a stuffing box and is connected to the cross member 31 at the rear of the front wedges 29. The cylinder 67 is filled with oil or other suitable liquid, and a small passage 20 71 is provided through the piston through which the liquid is forced as the piston traverses the cylinder during the rearward movement of the wedge frame.

With the mechanism above described a 25 single handle only is required for guiding the truck and for raising and lowering the table. The handle may be quickly and easily connected to the table elevating devices by a simple movement of the hand or foot 30 of the operator, and will be automatically disconnected therefrom by slightly raising the handle after the table has been elevated. By raising the handle to a greater extent it will cause the table to be lowered.

35 While the accompanying drawings illustrate and the foregoing specification describes what is now considered the preferred embodiment of the present invention, it is to be understood that the invention is not 40 limited to such specific mechanism, but may be embodied in the many other forms and arrangements of parts.

Having thus explained the nature and object of the invention, and specifically described 45 one form of mechanism in which it may be embodied, what is claimed is:

1. An elevating truck having, in combination, a carriage, a vertically movable table, a handle pivoted to turn about vertical and 50 horizontal axes, means for raising the table comprising a pivoted link, the link and handle being provided with coöperating surfaces for connecting the link to the handle whereby a downward movement of the 55 handle effects the raising of the table, and a spring for normally holding the link in raised position out of the path of movement of the handle.

2. An elevating truck having, in combination, a carriage, a vertically movable table, a longitudinally movable wedge frame provided 60 with wedges for raising the table, a handle carried by the carriage and pivoted to turn about a horizontal axis, said handle 65 being provided with projections on each side

near the horizontal pivot, a link pivotally connected at one end to the wedge frame and provided with an opening at its free end to receive the handle, and with hook-shaped recesses in the side walls of the 70 opening to receive the projections on the handle for actuating the wedge frame when the handle is depressed, a spring tending normally to raise the free end of the link, and means for depressing the free end of 75 the link against the action of the spring.

3. An elevating truck having, in combination, a carriage, a vertically movable table, a longitudinally movable wedge frame provided with wedges, a handle secured to the carriage and pivoted to turn about a horizontal axis, and a compound link comprising two members, one member pivotally connected to the wedge frame, and the other having one end pivoted to the free 80 end of the first member and having its free end adapted to be connected to the handle for actuating the wedge frame to elevate the table when the handle is depressed.

4. An elevating truck having, in combination, a carriage, a vertically movable table, a longitudinally movable wedge frame, a handle carried by the carriage and pivoted to turn about a horizontal axis, a link pivotally connected to the wedge frame, stops for 90 limiting the movement of the link, a spring normally tending to hold the link against one of the stops with the end of the link in position to be engaged by the handle to actuate the wedge frame to lower the table 95 when the handle is raised, and means for connecting the link and handle for actuating the frame to elevate the table when the handle is depressed.

5. An elevating truck having, in combination, a carriage, a vertically movable table, a vertically and longitudinally movable wedge frame provided with wedges having upper and lower inclined edges, rolls on the carriage engaging the under edges of the 100 wedges, devices on the carriage adjacent the rolls of greater height than the rolls to prevent lateral movement of the wedges, rolls 105 engaging the upper edges of the wedges, supports for the rolls secured to the table 110 and extending below the periphery of the rolls to prevent lateral movement of the wedges, and means for actuating the wedge frame to raise the table.

6. An elevating truck having, in combination, a carriage having rigidly mounted front and rear axles, guiding rolls rotatably supported upon the axles, devices mounted upon the axles adjacent the rolls and of greater height than the rolls, a vertically 120 movable table, a longitudinally movable wedge frame provided with wedges for raising the table, the lower edges of the wedges 125 engaging the rolls on the axles, rolls carried by the table for engaging the upper edges 130

of the wedges, and means for actuating the wedge frame to raise the table.

7. An elevating truck having, in combination, a carriage having front and rear axles, a steering knuckle pivotally mounted at each end of the front axle, a hollow steering pivot for the knuckle, a steering wheel carried by the knuckle, a vertically movable table, guiding devices carried by the table 10 and vertically movable in the hollow steering pivots, and means for raising and lowering the table.

8. An elevating truck having, in combination, a carriage having front and rear 15 axles, a steering knuckle pivotally mounted at each end of the front axle, a hollow steering pivot for the knuckle having an enlarged bore at its lower end, a vertically movable table, a guide rod carried by the 20 table and movable in the passage in the pivot, the rod being provided with a head movable in the enlarged bore, and means for raising and lowering the table.

9. An elevating truck having, in combination, a carriage, a vertically movable table, a longitudinally movable wedge frame provided with wedges for raising and lowering the table, a guiding handle arranged to 25 actuate the wedge frame in one direction 30 to elevate the table, and an abutment carried by the frame and normally in position when the table is held elevated to be directly engaged by the handle when the latter is raised, whereby the handle may move the 35 frame in the opposite direction to lower the table.

10. An elevating truck having, in combination, a carriage, a vertically movable

table, a handle carried by the carriage and pivoted to turn about a horizontal axis, 40 means for raising the table comprising a pivoted link, a hook on the free end of the link, means on the handle adapted to be engaged by the hook whereby a downward movement of the handle effects the raising 45 of the table, and a spring for normally holding the link in substantially vertical position in front of the table and out of the path of movement of the handle.

11. An elevating truck having, in combination, a carriage, a vertically movable table, a handle pivoted to turn about vertical and horizontal axes, means for raising the table comprising a pivoted link normally held out of the path of movement of 50 the handle, the link and handle being provided with coöperating surfaces for connecting the link to the handle to raise the table when the handle is lowered, and means on the link extending laterally therefrom 55 adapted to be engaged by the foot of the operator to connect the link to the handle.

12. An elevating truck having, in combination, a carriage, a vertically movable table, a steering handle mounted to turn 60 about a horizontal axis, means for raising the table comprising a pair of pivotally connected members, one provided on its free end with a hook and the other pivotally mounted, means on the handle to be engaged 65 by the hook to raise the table when the handle is lowered, means for holding the hook member normally out of the path of movement of the handle, and a spring for holding the other member in normal position.

BERNARD E. SCRIVEN.
